UNITED STATES PATENT OFFICE.

JOSEPH N. G. NESBIT, OF ATLANTA, GEORGIA.

NON-REFILLABLE BOTTLE.

1,243,965.

Specification of Letters Patent. Patented Oct. 23, 1917.

Application filed October 31, 1914. Serial No. 869,660.

To all whom it may concern:

Be it known that I, JOSEPH N. G. NESBIT, citizen of the United States, residing at Atlanta, in the county of Fulton and State of 5 Georgia, have invented certain new and useful Improvements in Non-Refillable Bottles, of which the following is a specification.

This invention relates to bottles of the nonrefillable variety, and contemplates as 10 its principal object the provision of bottles constructed after a principle which does not admit their being refilled after their first contents have been emptied.

A more specific object is to provide a bottle 15 having an enlarged cavity in its neck which is adapted to receive resilient means which will expand upon reaching such cavity to form an effectual guard for the automatic sealing means.

20 An object of equal importance with the foregoing is to provide bottles constructed with such regard to proportion, number and arrangement of parts as to render them capable of being cheaply manufactured as well 25 as durable and efficient in operation.

The above and additional objects which will become apparent as this explanatory description proceeds are accomplished by such means as are illustrated in the accompanying drawings, described in the following specification and then more particularly pointed out in the claims which are appended hereto and form a part of this application.

35 With reference to the drawings wherein there is illustrated the preferred embodiment of this invention as it is reduced to practice, and throughout the several views of which like characters of reference designate similar parts:—

Figure 1 is a vertical section through a bottle neck constructed in accordance with the disclosures of this invention,

Fig. 2 is a detail of the spring means 45 used in Fig. 1,

Fig. 3 is a view similar to Fig. 1, illustrating a further form this invention might take,

Fig. 4 is a plan view of the resilient 50 means employed in the second form,

Fig. 5 is a vertical section through a third form having spring means of a still different form,

Fig. 6 is a similar view of a fourth form, 55 Figs. 7 and 8 are views respectively in

plan and elevation of the blank of the spring means used in the last form, and

Fig. 9 is a perspective of the simple cork drawer effective for use in all of the forms.

Upon reference to the drawings there will 60 be seen illustrated four modifications of a single principle effective in the same manner and differing only in structural detail.

In each of Figs. 1, 3, 5 and 6 there will be noted a bottle 10 having the usual neck 11 65 which in the instance provided by this invention is formed with an enlarged central cavity 12 having the reduced passage 13 leading upward and exteriorly so that shoulders 14 are formed along the upper 70 perimeter of the cavity. Communicating with this recess 12 at its lower end is the frusto-conical passage way 15 which in turn leads to a reduced aperture 16 having direct communication with the interior of the 75 bottle 10. A small ball 17 is placed in the bottom of the passage 15 and is of such diameter as to project sufficiently into the aperture 16 to effectually prevent the introduction of any liquid from the outside when 80 the bottle is resting upon its base with the neck 11 in its usual upright position.

As a closure for the upper end of the passage 15 there is provided a stopper 18 85 preferably formed of cork and in the customary shape in order to maintain a tight wedging contact with the inner surface of the passage. A ball 19 is provided with a stem whereby the ball may be anchored to the cork 18 although spaced slightly from the upper surface of the latter in order to permit of the introduction therebetween of a tongs 20 as is illustrated to advantage in Fig. 9 comprising spaced arms 21 adapted to pass on either side of the stem for the ball 19, although not sufficiently spaced to pass around the ball itself, and a right angular shank or handle 22 affording a ready means for the user to insert the tongs into the cavity 12 for the purpose of drawing the cork 18 as is illustrated in Fig. 1. Between the closure cork and the ball valve 17 there is positioned in the passage 15 a loosely fitting float 23 the purpose of which will be hereinafter more fully described. 95

The enlarged cavity 12 is adapted to receive a number of different varieties of resilient means which accomplish in different manners a common purpose of permitting the raising of the stopper 18 sufficiently so 100 105 110

that a quantity of fluid may be poured from the bottle 10 but also preventing complete removal of the stopper 18 which would of course enable the bottle to be refilled contrary to the purpose of this invention.

In Fig. 1 there is illustrated resilient means 24 consisting of the expansible spiral spring illustrated in this figure and in Fig. 2, such spring having its inverted base fitting snugly within the upper perimeter of the cavity 12 against the shoulders 14 while its reduced end rests directly on the stopper 18 and tends to keep the latter in its proper position in the conical passage.

In Fig. 3 there is illustrated resilient means 25 as a substitute for the spring 24 in an otherwise similar embodiment of the non-refillable bottle. This means 25 consists simply of a curved or flanged metallic strip of such size as may be readily introduced through a suitable aperture formed in the stem of the ball cap 19 so that as shown in this figure, equal wing portions extend laterally for a sliding contact with the surface of the cavity 12 and are adapted to abut the shoulders 14 when the cork 18 is withdrawn in order to limit outward movement of the latter. It will be apparent that the resiliency of this means will permit of its introduction through the upper channel 13 very readily, the wings being in tension but after the cavity 12 has been reached the wings spring out and prevent removal in the obvious manner.

There is shown in Fig. 5 a resilient means 26 combining to some extent the structure of the two forms already shown since it includes a small number of coils preferably two or more, the ends of which terminate in wing portions as in the second mentioned form and performing the same functions. The coils are grouped between the head 19 and the top of the cork being readily positionable thereon after being introduced separately into the cavity 12. A fourth form is illustrated in Figs. 6, 7 and 8 and is formed from a blank such as will be noticed in the last mentioned figure including a rectangular resilient body portion 27 formed with opposed tongues 28 which are adapted to be bent similarly at right angles to the body portion which latter is rolled as shown in Fig. 7 into a form approximating a cylinder. The spaced meeting ends of the body portion afford the resiliency necessary to permit of the introduction of this resilient means to the passage 13 so that the device may properly expand upon reaching the cavities 12. The tongues 28 are provided in order to form better bearing surfaces between the body portion and the shoulders 14 and top of the cork 18 respectively.

From the construction described, it will be evident that a tilting of the bottle will permit the liquid contents to displace the

ball 17 and flow through the apertures 16 into the passage 15 passing the float 23 and in case the cork 18 has been withdrawn issuing from the mouth 13 of the bottle. Should anyone attempt however to fill the bottle again it will readily be seen that no matter what the position of the latter that the float 23 must always act to return the ball 17 to its seat and thus check the entrance of any liquid into the bottle portion 10 thus providing a construction capable of attaining the objects previously set forth.

While in the foregoing however, there has thus been illustrated in the drawings, and described in the specification such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

What is claimed is:—

1. In a non-refillable bottle having the neck thereof formed with a cavity, a reduced passage leading exteriorly therefrom, a reduced conical passage leading interiorly therefrom, a ball freely movable in said conical passage and capable of preventing inwardly directed communication therethrough, a cork adapted to be tightly seated in said conical passage above and spaced from said ball, a head connected to said cork to serve as a means for inserting the same into and removing it from said passage, and resilient means engaging said cork and extending laterally therefrom for contact with the walls of said cavity permitting a disengagement of said cork from its seat but preventing its entire removal from said conical passage.

2. A non-refillable bottle having the neck thereof formed with a cavity, a reduced passage leading exteriorly therefrom, a conical passage leading interiorly therefrom, a ball normally seated in the inner end of said conical passage to prevent inwardly directed communication therethrough but freely displaceable from its seat, float means movable in said conical passage and contacting with said ball, a cork normally closing the outer extremity of said conical passage, and means engaging said cork and extending outwardly therefrom to contact with the walls of said cavity to permit partial displacement of the cork from said conical passage but to prevent its complete removal therefrom.

3. In a non-refillable bottle, the combination with a bottle neck having a cavity formed midway therein, a passage leading exteriorly therefrom, a conical passage leading interiorly therefrom, a ball valve seatable in the inner end of said passage to prevent inwardly directed communication

therethrough, a float loosely contacting with said ball valve to seat the same under pressure of inflowing liquids, a cork located in the outer end of said conical passage permitting the outflow of liquid but preventing removal of said ball from said passage, and resilient means engaging the upper portion of said cork and the walls of said cavity to prevent total removal of said cork, of a manually insertible and removable imple-

ment to extend through said exterior passage into said cavity to withdraw said cork to the limit of said resilient means.

In testimony whereof I affix my signature in presence of two witnesses.

JOSEPH N. G. NESBIT.
